UNITED STATES PATENT OFFICE.

PETER STOLLE AND LENN A. MANLEY, OF MONETT, MISSOURI.

SWITCH SAFETY APPLIANCE.

Application filed November 27, 1925. Serial No. 71,685.

To all whom it may concern:

Be it known that we, PETER STOLLE and LENN A. MANLEY, citizens of the United States of America, residing at Monett, in the county of Barry and State of Missouri, have invented new and useful Improvements in Switch Safety Appliances, of which the following is a specification.

It is the purpose of the present invention to provide, in a switch safety appliance, a construction which, should the switch stand encounter any difficulty either with the connecting or head rods or the stand be destroyed, would prevent the switch point from shifting away from the rail of the main line.

Another purpose is to provide, in a switch safety appliance, a positive lock for the switch point only when the switch point is in contact with the rail of the main line.

Still another purpose is to provide, in an appliance of this character, a gravity returned locking element which, just so soon as the switch point leaves the rails of the siding and is in contact with the rail of the main line, will automatically drop into locking engagement with a moving member connected to the switch point for holding the member in a locked position as well as the switch point.

It is a further aim to provide an appliance which is very simple in construction and can be applied very easily and in a relatively short while.

A further purpose is to provide an appliance of this character which is foot-operable against the gravity means on the locking element so that, when the lever on the switch stand is actuated, the switch point may be moved to a position adjacent the rail of the siding.

A still further purpose is to provide an appliance which can be used in connection with a pushing actuator as well as a pulling actuator, which actuator in turn actuates a switch point.

Furthermore, it is the purpose to provide an appliance which can be manufactured at a relatively low cost and sold and installed at a reasonable profit, as the supporting plate and the fittings can be made of cast steel, it only being necessary to use wrought metal in the actuator or bar.

It is to be understood that the particulars herein given are in no way limitative and that, while still keeping within the scope of

the invention, any desired modification of details and desired proportions may be made in the apparatus according to the circumstances.

The invention comprises further features and combinations of parts to be hereinafter set forth, shown in the drawings and claimed.

In the drawings:

Figure 1 is a view in perspective of a portion of a track with a switch point and illustrating the improved safety appliance applied.

Figure 2 is a plan view.

Figure 3 is a sectional view transversely through the rails and the switch point and showing the locking element in engagement with the actuator or bar which is connected to the switch point.

Figure 4 is a sectional view through the safety appliance at right angles to that shown in Figure 3.

Figure 5 is an enlarged detail perspective view of the plate which is mounted upon the tie, whereby practically all the parts of the safety appliance are substantially flush with the surface of the tie.

Figure 6 is a detail view of the locking element.

Referring to the drawings, 1 designates the switch point which cooperates with one of the rails of the main line and is adapted for the purpose of causing a train to shift onto a siding when the switch point is moved for such a purpose, and 2 denotes the safety appliance as a whole which comprises a plate 3 which is supported on a tie 4, being secured thereon by spikes 5 passing through rectangular openings 6 which are formed in the plate.

Riveted at 7 and 8 to the plate 3 are transverse plates 9 and 10. The plate 9 has upstanding ends 11 and 12 which have openings. The plate 10 at its opposite ends has trunnions 14 and 15, and fulcrumed upon the trunnion 14 is a locking element or lever 16 which is capable of corresponding mounting on the trunnion 15. For instance, if the safety appliance is to be applied to a switch wherein the switch point is pushed instead of pulled, the locking element may be fulcrumed upon the trunnion 15, and the plate may then be placed so that the locking element may properly cooperate with the actuator which is connected to the switch point. For the purpose of holding the lock-

ing element on the trunnion, a washer 17 is used, there being a cotter pin or key 18 passed through the trunnion in the manner shown in the drawings.

5 The locking element has a foot engaging piece or plate 19 at one end and a weight or gravity member 20 at the other end. In fact, the weight or gravity member is carried by the end of the longer arm of the element. The locking element has an opening 21 which may cooperate with the opening of either of the upstanding ends 11 and 12. For instance, if the appliance is used in connection with a pulling switch, the locking 10 element cooperates with the opening in the upstanding end 11, and if it is applied to a pushing switch, it cooperates with the opening in the upstanding end 12. In either case, the shackle of a padlock 22 engages 15 with the registering openings in the upstanding end and the locking element to hold the latter in its normal position for locking the pushing or pulling actuator in normal position, whereby the switch point is held in 20 close contacting position with the rail of the main line.

25 The plate 3 of the appliance may be any size and shape and constructed of any suitable metal, and is formed with a guide channel 23. This channel is constructed at the time the plate is cast. For instance, the plate has a depending part 24 which lies against a side face of a tie and in which the channel or guide is formed at the time the 30 channel or guide is formed at the time the plate is cast. This channel slidably receives either a pulling or pushing member or bar 25, with one edge protruding sufficiently 35 above the surface of the plate 3 to enable the locking element to engage in a notch 26 formed in the bar 25.

40 The bar is connected at 27 to the switch point and extends laterally therefrom and under the rail of the main line (but not connected to it) and is of sufficient length to engage in the channel or guide 23. The 45 notch is formed in the bar at such a location that when the switch point is in contact with the rail of the main line, the locking element will engage with the notch, but when 50 the switch point is moved out of contact with the rail of the main line for the purpose of shifting the train to the siding, it is impossible to engage the locking element with 55 the notch.

55 By virtue of a safety appliance of this character, it avoids the necessity of locking the lever on the switch stand and at the same time constitutes a more positive lock with greater safety due to the fact that should 60 the switch stand become damaged in any manner, the switch point remains in contact with the rail of the main line as long as the padlock is in engagement with the registering openings upstanding end and locking element.

For illustrative purposes, the drawings show the appliance used in connection with a stand which is mounted upon two ties, but it is to be borne in mind that the appliance can be employed in connection with a switch 70 stand which is mounted on a single tie.

75 The gravity member or weight on the locking element causes it to automatically fall into engagement with the notch as soon as the switch point contacts with the rail of the main line so that, regardless of whether or not the heel of the switch point is properly maintained, this appliance will hold the switch point securely against the rails 80 of the main line.

85 When a padlock is engaged with the registering openings upstanding end locking element, the switch is fool-proof and locked just the same as if the lock was placed on a switch stand. Practically all the parts of 90 the safety appliance are substantially flush with the tie, thereby preventing anything that might be dragging along the track, either between the rails or on the side of the rails, from getting caught in any of the 95 parts.

99 The bar 25, where it connects with the switch point, has an angularly bent end 28 conforming to the base of the switch point. The bar, in extending from the switch point, is disposed flatwise, but at a point midway its ends it is provided with a twist 29, so that the portion of the bar beyond the rails will be positioned vertically.

100 The invention having been set forth, what is claimed is:

1. In a safety appliance for switches, the combination with a switch point and an actuating bar therefor of which the latter is provided with a notch, of a plate for secure- 105 ment to the top face of a tie and provided with a depending guide channel in which said bar slides, a locking element fulcrumed on the plate and overhanging the bar for en- 110 gagement with a notch formed therein, the locking element being provided with a terminal weight, and with an opening register- 115 able with an opening formed in an upstand- 120 ing element carried by the plate for the re- 125 ception of a locking shackle when the lock- 130 ing element is engaged in the notch of said bar.

2. In a safety appliance for switches, the combination with a switch point and a mov- 120 able bar connected to it, the bar having a notch, of a plate for securement to a tie of a track and provided with a guide for said bar, a gravity actuated locking element ful- 125 crumed upon the plate for actuation toward and engagement with the notch for retaining the switch point in contact with a rail of a main line, an auxiliary plate on the first plate and having an upstanding apertured end, the locking element having an opening 130 registering with the aperture in the upstand-

ing end, and means for engaging the registering opening and aperture for locking the element in engagement with the notch.

3. In a safety appliance for switches, the combination with a switch point and a movable bar connected to it, the bar having a notch, of a plate for securement to a tie of a track and provided with a guide for said bar, a gravity actuated locking element fulcrumed upon the plate for actuation toward and engagement with the notch for retaining the switch point in contact with a rail of a main line, an auxiliary plate on the first plate and having an upstanding apertured end, the locking element having an opening registering with the aperture in the upstanding end, and means for engaging the registering opening and aperture for locking the element in engagement with the notch, said element having a foot engaging plate on the end opposite its gravitating end, whereby the element may be actuated when released to disengage from the notch.

4. In a safety appliance for switches, the combination with a switch point and a movable bar connected to it, said bar having a notch, of a plate for securement to ties of the main line, a pair of auxiliary plates fastened on the first plate, one of said auxiliary plates having an upstanding apertured end, and a gravitating locking element fulcrumed upon the other auxiliary plate and having long and short arms, the longer arm being the gravitating end of the element for

engagement with the notch to hold the switch point in contact with a rail of a main line, the shorter arm having a foot engaging plate for tilting the element against the gravitating longer arm to disengage the element from the notch.

5. In a safety appliance for switches, the combination with a switch point and a movable bar connected to it, said bar having a notch, of a plate for securement to ties of the main line, a pair of auxiliary plates fastened on the first plate, one of said auxiliary plates having an upstanding apertured end, a gravitating locking element fulcrumed upon the other auxiliary plate and having long and short arms, the longer arm being the gravitating end of the element for engagement with the notch to hold the switch point in contact with a rail of a main line, the shorter arm having a foot engaging plate for tilting the element against the gravitating longer arm to disengage the element from the notch, said element having an opening registering with the aperture of the upstanding end, and means for engaging with the registering opening and aperture for locking the element when it is engaged with the notch, the first named plate having an elongated guide in which the bar slidably engages.

In testimony whereof we affix our signatures.

PETER STOLLE.
LENN A. MANLEY.
